SELF REGULATED HEAT TRANSFER
SYSTEM

Samuel P. Miller, Chicago, Ill.

Application May 15, 1936, Serial No. 79,842
In Canada January 27, 1936

29 Claims. (Cl. 237—9)

My invention relates to improvements in self regulated heat transfer systems and has for a particular object the provision of a heat transfer system in which the pressure or degree of 5 vacuum through the entire system may be maintained at a substantially uniform and predetermined point without any human intervention.

This application is a continuation in part of my application for patent on "Self regulated heat 10 transfer systems", Serial No. 699,557, first filed in the United States Patent Office on November 24, 1933, and renewed on April 25, 1936, and my application for patent on "Heat transfer systems," 15 Serial No. 1,091, filed in the United States Patent Office on January 10, 1935.

Another object is to provide such a system at a very small cost and one which may be employed with known heat transfer systems without occasioning expensive changes.

20 Another object of my invention is to provide a heat transfer system in which the pressure in the secondary steam line may be maintained at a very low point, even below atmosphere, and yet provide sufficient heat for the transfer system.

25 The expansion of steam as used in the ordinary steam heating system of today causes a loss in the amount of steam necessary for the work, due to the fact that being controlled from the near end only, expansion of steam through 30 the entire header and riser system results, which accounts for the greatest amount of the so-called friction in the lines, since expansion causes friction, and expanding steam also creates a non- 35 condensable gas which is lighter than expanded steam and which therefore goes to the top of radiators. The dew formed of expanded steam goes to the bottom of the radiators, keeps the 40 thermostatic traps shut off due to the heat content, and therefore the gases are not removable by the ordinary vacuum pump. Expansion causes absorption from the steam to the water, 45 ordinarily called refrigeration, therefore requiring more steam to do the same work than when there is less expansion of the steam. Expansion causes large amounts of water to be condensed in headers and risers, due to this expansion and refrigeration, and this water will not be re-evaporated. In other words, if the steam is kept 50 from expanding in headers and risers, no steam will turn to water, and if it did, due to radiation, it would re-evaporate into steam.

In my invention I stop the larger parts of these losses due to expansion by connecting the 55 headers and risers at the near end and the far

end with the control valve diaphragm through a control or biasing means whereby headers, risers, and far end return lines, either one affecting the reducing valve or control means, cause more or less steam to be delivered to the headers because 5 one ounce of variation of the control or biasing means would affect the reducing valve diaphragm to the extent of eight ounces, due to the diameter of the reducing valve diaphragm which is not less than eight inches. Three ounces less 10 pressure on the diaphragm than the valve is set for would open the valve wide open. Therefore I would have the risers and headers all full of steam at not less than one ounce difference from end to end to maintain the equilibrium 15 of the valve setting. Therefore the entire expansion of the steam in the headers and risers would not exceed one ounce which would not set up much absorption and refrigeration; also it would not drop much or any water in the 20 headers and risers. This also stops the boiling of the water in the return lines because the water does not absorb heat from the steam in the quantities it would under expansion of the steam, and the returns will operate so near the 25 pressure in the headers and risers the difference in the boiling points at the different pressures between the two would not permit the same.

Regulating valves are very old in the heating art, and it is well known that they are employed and interposed between a primary steam pressure line and a secondary steam pressure line. The primary steam pressure line ordinarily conducts steam from a boiler or other source of steam at a considerably higher pressure than is 30 desired to be introduced into the secondary steam pressure line; the regulating valves just mentioned are designed to effect such a reduction of pressure and maintain in the secondary line a substantially uniform and predetermined pressure 35 regardless of the pressure in the primary line. These regulating valves are ordinarily provided with a manually operable set wheel by which the operator or engineer sets the valve to maintain a desired pressure in the secondary 40 line. It has been found, however, that regardless of the skill and knowledge employed in making regulating valves and heating systems, pressures at various points throughout the heat transfer system vary a considerable degree. This 45 variation is most noticeable, of course, between a point close to the beginning of the secondary steam line and the far end of the secondary and risers where condensed steam is collected for re-evaporation. A cause of the variation in pres- 50 55

sure and temperature is the friction offered by the steam line to the passage of steam therethrough. As before stated one of my objects is to provide a heat transfer system in which variations in pressure and temperature or degree of vacuum throughout the system are substantially eliminated, and in which the pressure or degree of vacuum may be automatically maintained at a predetermined point.

Some heat transfer systems are commonly known as vacuum systems and are in wide use. Some of these systems employ exhaust steam from a power generating engine to supply heating systems or other heat transfer systems. In the type of system just mentioned the primary steam line from the boiler or other source of steam is provided with a by-pass, one side of which supplies steam to a power generating engine under boiler pressure, and the other side of which supplies steam under the same pressure to a reducing or regulating valve, which in turn communicates with the main secondary steam line. The exhaust steam from the power generating engine is received in a tank also communicating with the main secondary steam line. A vacuum is preferably maintained in the secondary steam line and exhaust steam receiving tank in order to increase the efficiency of the power generating engine and the heat transfer system. With my system steam may be delivered from the boiler to the heat transfer system at as much as ten inches of vacuum, if desired; the vacuum may be maintained at a constant degree by the automatic opening and closing of the regulating or reducing valve interposed between the primary from the boiler and the main secondary steam line. It can be seen that such a result is highly desirable and increases the efficiency of the power generating engine and heating system as well.

My invention may be understood clearly from the following specification and drawings, in which:

Fig. 1 is a somewhat diagrammatic layout of a heat transfer system employing my regulating means;

Fig. 2 is a detail view in section of the pilot valve of a conventional type regulating valve with some of my connections attached thereto;

Fig. 3 is a sectional view of a conventional type of check valve employed for preventing the water, pressure, or vacuum in the condensation chamber from affecting the pressure or vacuum of the heat transfer system;

Fig. 4 is a diagrammatic view of a modified steam heating system embodying the principle of my invention; and

Fig. 5 is a vertical sectional view of the control and reducing valve of said system shown in detail.

Referring particularly to Figs. 1, 2, and 3, a conventional type boiler 5 may be employed to deliver steam to a primary steam line 6 which is connected to the high pressure side of a regulating valve generally indicated at 7. A secondary steam line 8 is connected to the low pressure side of regulating valve 7. Secondary line 8 is connected at its far end with a pipe 9 which empties into a condensation chamber 10. Branch steam lines 11 conduct steam from secondary line 8 to a multiplicity of steam consuming units or radiators 12, and the ends of branch pipes 11 are received by a condensate manifold pipe 13 which empties into a pipe 14. The pipe 14 empties into

condensation chamber 10, and a check valve 15 is arranged in line 14 for the purpose above mentioned. Various return pipes 16 conduct condensed and used steam from the heat consuming units 12 and empty into return manifold 17 which empties into a return line 18 having its lower end communicating with condensation chamber 19. A similar check valve 20 is arranged in return line 18.

The particular type of regulating valve illustrated is typical of the construction employed in regulating valves although various types employ some modification in structure. Referring now to Fig. 2 the regulating valve 7 is under the control of a pilot valve 21 whose stem 22 extends upwardly through a guide web 23 and into a diaphragm chamber 24. The upper end of the stem 22 abuts against a diaphragm 25. The lower end of the stem 22 extends into a spring housing chamber 26 and is encircled by a coil spring 27. A collar 28 is pinned to the stem, and the compression spring 29 presses upwardly on collar 28 to urge the valve 21 to a closed position on valve seat 29. A spring urged disk 30 seats on the upper face of diaphragm 25 and is provided with a stem guide 31 for the sliding reception of a screw stem 32. A compression spring 33 is arranged on screw stem 32 and seats in a groove 34 on the upper face of disk 30. The upper end of spring 33 seats against a follower 35 which carries a longitudinally threaded bore 36 into which stem 32 is turned. A pair of guide lugs 37 on follower 35 seat in appropriate grooves of housing 38 and prevent the rotation of said follower.

A steam line 39 extends from high pressure side of the regulating valve 7 to the valve chamber 40 of pilot valve 21. The opening of the pilot valve 21 permits steam from the high pressure side to pass into outlet chamber 41 and thence into steam line 42. The steam line 42 communicates with the lower end of a cylinder 43 shown in Fig. 1 and drives piston 44 upwardly. A main valve stem 45 is connected to piston 44 at one end and a main valve 46 at its opposite end. Valve 46 in closed position seats on main valve seat 47 and prevents the passage of steam from high pressure primary to the lower pressure secondary. However, when steam proceeds through pipe 42 and pushes piston 44 upwardly, the valve 46 is opened and steam is permitted to proceed from the primary to the secondary. A hand wheel 48 is employed to turn screw stem 32 so as to force follower 35 downwardly against compression spring 33 and depress diaphragm 25. The depression of diaphragm 25 causes pilot valve 21 to be unseated in order to admit steam to outlet chamber 41 for action upon piston 44.

The novel part of my invention and the part which enables the accomplishment of startling results is the following described system of intercommunicating by-passes. A pipe 49 of relatively small dimensions is arranged to conduct steam from secondary pipe 8 to a T fitting 50. A pipe 51 is connected with one end of T fitting 50 and has its opposite end communicating with diaphragm chamber 24 heretofore described. A pipe 52 is connected to the other end of T fitting 50 and has its opposite end communicating with a T fitting 53. A pipe 54 extends between pipe 52 and a T fitting 55 arranged in pipe 18. A pipe 56 is connected at one end with T fitting 53 and at its opposite end with a T fitting 57 which is arranged in pipe 9.

The operation of my system as described above is as follows: The hand wheel 48 is turned so as to depress diaphragm 25 and valve 21 a sufficient distance to permit a desired pressure in secondary steam line 8. Steam from the primary 5 passes through pipe 39, pilot valve chamber 40, outlet chamber 41, pipe 42, and pushes upwardly on piston 44 in cylinder 43. Main valve 46 is thus opened and steam passes into the secondary 10 and likewise into cylinder 43. The pressure on the upper face of piston 44 tends to force it downwardly and thus decrease the opening of main valve 46. The steam passing into secondary 15 8 passes through the various pipes 11, steam consuming units 12, manifold 13, far end 9, return manifold 17, return pipe 18, pipe 14, and thence into condensation collecting chambers 10 and 19. However, steam also passes from secondary 20 8 to pipe 49 and to T fitting 50. Since the tension 25 of coil spring 33 opposes the raising of diaphragm 25 by the steam pressure passing through T fitting 50 and pipe 51 to diaphragm chamber 24, the steam follows the line of least resistance and passes through pipe 52 to T fitting 53. As before 30 stated T fitting 53 by-passes steam from line 52 to pipe 18, which is connected with return manifold 17 which collects water of condensation from the various steam consuming units, and to pipe 56 which communicates with T fitting 35 57 arranged in pipe 9; pipe 9 is the far end of secondary line 8. When steam through pipe 52 reaches T fitting 53 it will again follow the line of least resistance, or enter the pipe having the smallest pressure therein, and will continue to 40 do so until the pressures in pipes 18 and 9 are equalized. As soon as the pressures in pipes 18 and 9 are sufficiently great, the pressure in pipe 52 supplied through pipe 49 will be exerted through pipe 51 and cause the passage of steam 45 into diaphragm chamber 24, the steam pressure on diaphragm 25 will cause the raising of diaphragm 25 when the pressure becomes sufficiently great, and when this occurs compression spring 27 will urge valve stem 22 upwardly and 50 urge pilot valve 21 toward its seat 29. It should be noted carefully, however, that no closing action on pilot valve 21 will occur until an equalization of pressure and a building up of sufficient pressure have been accomplished as above set out. 55

Under certain circumstances, particularly moderately sized systems, it is possible to omit pipe 56, and under other circumstances to omit pipe 54. Under these conditions I have found that satisfactory operation of the control valve 55 will result with pipe 52 connected either to pipe 9 or 18 as the particular condition may warrant. 60

A check valve 58 prevents water of condensation, pressure, or vacuum in the condensation chamber from affecting the heating system 65 through return steam line 9; it is similar in construction to check valves 15 and 20. The construction of these check valves is shown clearly in Fig. 3, and each comprises a housing 59, removable cap plug 59a, check ball 59b, and valve seat 59c. An intake nipple 59d is adapted to be connected to a communicating pipe connection, and a nipple 59e is adapted to be connected to an outlet pipe connection. The rise of liquid on the lower side of check ball 59b will cause it to 70 become unseated and permit the liquid to enter the outlet pipe connection. The reverse is not true, however, because any pressure on the top side of check ball 59b could not have any unseating function. The pressure on the communicating side of the valve is usually higher

than the pressure on the outlet side, and this, of course, aids in unseating the check ball when necessary. The presence of excess water in steam lines makes it difficult to maintain a balanced pressure throughout the heat transfer system, 5 and it is desirable to employ check valves and condensation collecting chambers in order to remove water from steam lines.

I am aware that exhaust steam has been used at above atmospheric pressure for heating systems, but to my knowledge no one has ever controlled exhaust steam for a heating system at sub-atmospheric pressure, and especially by means which I have provided. Among the advantages are the efficient and economical heat and reduction of back pressure on the engine generating the exhaust steam. The initial pressure steam may be reduced from thirty-five pounds to at least nineteen pounds per hour per horsepower at definite inches of vacuum. The arrangement which I have provided entirely eliminates all the disadvantages of the necessity of using water for condensation in the cases where exhaust steam is used for heating or process work at above atmospheric pressure.

The means which I have provided are simple. I have provided a riser and return and radiator structure which is conventional, and I have also provided a conventional reducing valve. I have connected the return line and the diaphragm 30 of the conventional reducing valve with a control or by-pass pipe, and this pipe I have connected with a vacuum pump, and have provided a thermostatic trap valve in the line of the vacuum pump of the control or by-pass line. The thermostatic trap valve may be set to open at a definite temperature and cause the vacuum pump to operate to cause the control line to exert increased suction on the diaphragm of the reducing valve to admit additional steam as desired.

I have provided means for controlling the desired amount of vacuum in the heating system to admit steam from a primary line through a reducing valve and by my system exhaust steam may be used as far as it will go and if there is 45 too much of it at certain times a safety valve may be provided. If the exhaust steam is not sufficient, steam is automatically admitted from the primary line.

In my system the diaphragm of the reducing 50 valve of the primary line may also be placed in multiple series with the entire load. The near and far ends of the secondary line may be placed in series by means of the control or by-pass pipe to allow an equalizing of pressure between the 55 near and far ends of the secondary line to be registered on the control or by-pass line. Thus the diaphragm in the reducing valve of the primary line being in communication with the control or by-pass line the pressure on the diaphragm will vary according to the rate of condensation in the condensing units.

When the thermostatic trap valve opens, both 60 ends of the secondary line and one side of the diaphragm are placed in communication with the vacuum pump, allowing the vacuum pump to lower the pressure underneath the diaphragm and throughout the secondary line, which allows the reducing valve to deliver more steam from the primary line to the secondary line. 65 When the heat rises in the control line to a set number of degrees, the thermostatic trap valve closes, cutting off the pump from communication with the control or by-pass line. I have provided a thermostatic trap valve for each 70 75

radiator so that when the steam reaches the desired temperature the trap will close and it will be impossible to draw further steam through the radiator. The vacuum pump will not only assist in exhausting air and condensation speedily, but will assist in automatically maintaining the desired vacuum, as will be manifest to those skilled in the art, in view of the following description.

In the modified form shown in Figs. 4 and 5, exhaust steam may be led from a prime mover through an exhaust line 60 to a hot water tank 61 and outlet pipe 62. From pipe 62 the exhaust steam may be led into an exhaust manifold 63 connected with a secondary 64, and the manifold 15 may also communicate with a safety exhaust pipe 65 having a safety valve 66 to furnish an outlet for excess exhaust steam. The secondary 64 leads to a radiator manifold pipe 67 and a far end pipe 68 provided with an adjustable thermostatic trap 20 valve 69. I claim no invention in the trap itself as these traps are old and well known and adapted to close under various temperatures to prevent the passage of steam. Far end pipe 68 leads to a condensation pipe 70 and a pump feed pipe 71, 25 which in turn is adapted to feed condensation to a conventional vacuum pump 72. The vacuum pump 72 in turn is provided with a discharge pipe 73 which leads to a conventional air extractor 74 on the tank 61, and thereafter leads to the tank 30 61 itself. The tank 61 is provided with a hot water discharge pipe 75 which leads to a pump 76 adapted to pump hot water through a hot water discharge pipe 77 leading to a steam boiler.

The radiator manifold pipe 67 is adapted to 35 feed steam into a plurality of radiator branch pipes 78 and radiators 79. The radiator branch pipe 78 is provided with a thermostatic trap valve 80 which may be similar to the trap valve 69 and which will function in a similar manner. The 40 radiator branch pipes 78 lead to condensation pipe lines 81 which in turn lead to a return manifold line 82 which in turn is connected to condensation pipe line 70.

Each radiator is provided with a thermostat 45 control trap valve 83 which may be similar to the traps 69 and 80 and function in a similar manner. The radiators communicate with condensation pipes 84 which in turn communicate with return manifold line 82. A by-pass pipe 85 leads from far end pipe 68 to the exhaust manifold 63.

A by-pass condensation pipe 86 is provided to communicate with pump feed pipe 71 and by-pass pipe 85, and is provided with an adjustable thermostatic trap valve 87, and the by-pass condensation pipe 86 is also provided with a check valve 88 adapted to prevent condensation and such from backing into the pipe 86 from pipe 71.

The by-pass pipe 85 communicates at its other 60 end with a diaphragm pipe 89 which leads to the pressure compartment 90 of a diaphragm casing 91 in a live steam valve structure 92 as shown in detail in Fig. 5. In the diaphragm casing 91 there is provided a diaphragm 93 which creates not only the steam pressure compartment 90 but 65 also an atmospheric pressure compartment 94. The diaphragm 93 has connected to it a vertical post 95 which is operatively connected to a balance lever 96 provided with weights 97 in a manner which will be manifest to those skilled in the art.

Resting on the post 95 or operatively connected to it is a valve stem 98 which is located in and travels in a bore 100 in the usual packing 99 and 75 the valve structure body. The stem 98 at its

upper end is enlarged as at 101 and is provided with a pair of valves 102 seating in a pair of valve seats 103 in the valve structure body 92. The valve structure body 92 is provided with an inner chamber 104 communicating with a live steam line 105 from a steam boiler not shown. The valve structure body 92 is also provided with an outlet chamber 106 communicating with a pipe line 107 connected to one end of the exhaust manifold 63.

This same structure in detail may be used with 10 the same vacuum conditions throughout the system when using live steam direct from boilers instead of exhaust steam. In the operation of my system the reducing valve structure 92 may be set at ten inches of vacuum, and the vacuum 15 pump may be set to maintain a vacuum of twelve inches. This arrangement will allow a temperature of steam in the control or by-pass line 85 to be maintained at the temperature of steam at ten inches of vacuum. When the thermostatic 20 trap valve 87 starts to open at this temperature, this will allow the twelve inches of vacuum in the return lines to pass to the control or by-pass line and lower the pressure in the secondary line and underneath one side of the diaphragm of the reducing valve structure 92, causing the valves 102 to admit more steam to the system until the temperature in the control line has reached the set temperature, when the thermostatic trap 25 will be closed, cutting off the vacuum pump from the control or by-pass line 85. The thermostatic trap valve will be balanced to maintain the degrees of heat throughout the heating system at the 30 temperature of steam at which the reducing valve is set.

If the temperature at any individual radiator 35 thermostatic trap valve lowers beyond the set temperature, its trap valve will open and the twelve inches of vacuum will operate to draw the necessary steam into the particular radiator, insuring that each radiator shall have the desired amount of steam, regardless of its condition or 40 distance from the source of steam supply.

It will be apparent that under operating conditions a drop in temperature and pressure in the 45 control line will open trap valve 87 and that this drop may be occasioned by a drop in the manifold 63 or in the far end pipe 68. Also if there is sufficient drop in pipe 68, trap valve 69 may be opened. Thus the control valve 92 may be opened 50 by the actuation of either valve 69 or 87. In practice, valve 69 will ordinarily be a considerable distance away from valve 87 so that the latter may be more sensitive to temperature changes in manifold 63 than will valve 69. Valve 69 will preferably be set at the temperature desired to be maintained in manifold 68 and secondary 64 and valve 87 will be set slightly lower. Thus if a sudden drop occurs in the system near secondary 64 and manifold 63, valve 87 will open and the full effect 55 of the vacuum pump 62 will be transmitted to valve 92 and open it wide open, if necessary, to bring up the temperature or degree of vacuum to balance. If, however, a small drop occurs in the region of far end pipe 68, valve 69 will open and 60 unbalance the control line 85 only an amount necessary to unseat valve 92 and consequently admit only the required amount of steam to restore the system to normal.

It will be apparent that far end pipes 9 and 68 70 do not necessarily need to be separate pipes but may be combined with the last riser 11 or 78. In these cases the control line 52 or 85 would be connected to the last riser 11 or 78 and the system would function exactly as described.

By the operation of the system as described, it will be clear that the entire secondary line will be maintained at the temperature and pressure that the control valve is set at. There will consequently be no expansion of steam in the secondary line and risers except a negligible amount, as the control valve is operated upon the slightest unbalancing of pressure or temperature in the control pipe; and because expansion is prevented in this manner the operation of the system will be greatly improved with resulting increase of efficiency.

In installations where the foregoing described systems are in operation, uniform savings of ten per cent. and in many instances of fifteen to thirty per cent. have been realized.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a heat transfer system having a primary steam line, a secondary steam line, a regulating valve interposed between said primary steam line and said secondary steam line and having a diaphragm actuated pilot valve therefor, said pilot valve being constructed and arranged to close the regulating valve upon an increase in pressure exerted against said diaphragm, and return steam means, the combination of a communicating pipe connection from near the beginning of said secondary steam line to one side of said diaphragm, and a by-pass connection between said last mentioned pipe connection and said return steam means arranged to allow passage of steam from the former to the latter.

2. In a heat transfer system having a primary steam line, a secondary steam line, a regulating valve interposed between said primary steam line and said secondary steam line and having a diaphragm actuated pilot valve therefor, said valve being constructed and arranged to close the regulating valve upon an increase of pressure exerted against said diaphragm, and return steam lines including the far end of said secondary steam line, the combination of a communicating pipe connection from near the beginning of said secondary steam line and one side of said diaphragm, by-pass connections between said communicating pipe connection and said return steam lines, and by-pass connections between said return steam lines and the far end of said secondary steam line, said by-pass connections being arranged to allow passage of steam from the communicating pipe connections to said return steam lines including the far end of said secondary line.

3. In a heat transfer system having a plurality of radiators, a steam supply pipe, and a return pipe therefor, the combination of a control valve in said supply pipe and having a diaphragm chamber, a diaphragm in said chamber, and means connecting said valve and said diaphragm and adapted to close said valve on an increase in the pressure in said chamber and open said valve on a decrease in the pressure in said chamber, a control pipe connected to said chamber and to said supply pipe, and a return pipe connection to said control pipe having a thermostatic trap valve therein.

4. In a heat transfer system having a plurality of radiators, a steam supply pipe, and a return pipe therefor, the combination of a control valve in said supply pipe and having a diaphragm chamber, a diaphragm in said chamber, and means connecting said valve and said diaphragm and adapted to close said valve on an increase in the pressure in said chamber and open said valve on a decrease in the pressure in said chamber, a control pipe connected to said chamber and to said supply pipe, a return pipe connection to said control pipe having a thermostatic trap valve therein, and a vacuum pump connected to said return pipe.

5. In a heat transfer system having a plurality of radiators, a steam supply pipe, and a return pipe therefor, the combination of a control valve in said supply pipe and having a diaphragm chamber, a diaphragm in said chamber, and means connecting said valve and said diaphragm and adapted to close said valve on an increase in the pressure in said chamber and open said valve on a decrease in the pressure in said chamber, a control pipe connected to said chamber and to said supply pipe, a return pipe connection to said control pipe having a thermostatic trap valve therein, a vacuum pump connected to said return pipe, and a thermostatic trap valve in said return pipe.

6. In a heat transfer system having a plurality of radiators, a steam supply pipe having a far end, and a return pipe therefor, the combination of a control valve in said supply pipe and having a diaphragm chamber, a diaphragm in said chamber, and means connecting said valve and said diaphragm and adapted to close said valve on an increase in the pressure in said chamber and open said valve on a decrease in the pressure in said chamber, a control pipe connected to said chamber and to said supply pipe, and a far end pipe connection to said control pipe.

7. In a heat transfer system having a plurality of radiators, a steam supply pipe having a far end, and a return pipe therefor, the combination of a control valve in said supply pipe and having a diaphragm chamber, a diaphragm in said chamber, and means connecting said valve and said diaphragm and adapted to close said valve on an increase in the pressure in said chamber and open said valve on a decrease in the pressure in said chamber, and a control pipe connecting said chamber, said supply pipe, said far end pipe, and said return, said control pipe and return connection having a thermostatic trap valve therein.

8. In a heat transfer system having a plurality of radiators, a steam supply pipe having a far end, and a return pipe therefor, the combination of a control valve in said supply pipe and having a diaphragm chamber, a diaphragm in said chamber, and means connecting said valve and said diaphragm and adapted to close said valve on an increase in the pressure in said chamber and open said valve on a decrease in the pressure in said chamber, a control pipe connecting said chamber, said supply pipe, said far end pipe, and said return, said control pipe and return connection having a thermostatic trap valve therein, a vacuum pump connected to said return, and a thermostatic trap valve connecting said far end and said vacuum pump.

9. In a heat transfer system having a plurality of radiators, a steam supply pipe having a far end, and a return pipe therefor, the combination of a control valve in said supply pipe and having a diaphragm chamber, a diaphragm in said chamber, and means connecting said valve and said

diaphragm and adapted to close said valve on an increase in the pressure in said chamber and open said valve on a decrease in the pressure in said chamber, a control pipe connecting said chamber, 5 said supply pipe, said far end pipe, and said return, said control pipe and return connection having a thermostatic trap valve therein, a vacuum pump connected to said return, and an adjustable thermostatic trap valve connecting said far end and 10 said vacuum pump.

10. In a heat transfer system having a plurality of radiators, a steam supply pipe having a far end, and a return pipe therefor, the combination of a control valve in said supply pipe 15 and having a diaphragm chamber, a diaphragm in said chamber, and means connecting said valve and said diaphragm and adapted to close said valve on an increase in the pressure in said chamber and open said valve on a decrease in the pressure in said 20 chamber, a control pipe connecting said chamber, said supply pipe, said far end pipe, and said return, a vacuum pump connected to said return, a thermostatic trap valve connecting said far end and said vacuum pump, 25 and a by-pass connection between said control pipe and said vacuum pump having a thermostatic trap valve therein.

11. In a heat transfer system having a plurality of radiators, a primary supply pipe therefor, a secondary supply pipe therefor having a far end and a return for said radiators, the combination of a control valve having a diaphragm chamber, a diaphragm in said chamber, and means connecting said valve and said diaphragm 35 and adapted to close said valve on an increase in the pressure in said chamber and open said valve on a decrease in the pressure in said chamber, and means to prevent expansion of steam in said secondary, comprising a control pipe connecting 40 said diaphragm chamber, said secondary supply, and said return, said control pipe and return connection having a thermostatic trap valve therein.

12. In a heat transfer system having a plurality of radiators, a primary supply pipe therefor, a secondary supply pipe therefor having a far end and a return for said radiators, the combination of a control valve having a diaphragm chamber, a diaphragm in said chamber, and means connecting said valve and said diaphragm 50 and adapted to close said valve on an increase in the pressure in said chamber and open said valve on a decrease in the pressure in said chamber, and means to prevent expansion of steam in said secondary, comprising a control pipe connecting 55 said diaphragm chamber, said secondary supply, and said far end.

13. In a heat transfer system having a plurality of radiators, a primary supply pipe therefor, a secondary supply pipe therefor having a far end and a return for said radiators, the combination of a control valve having a diaphragm chamber, a diaphragm in said chamber, and means connecting said valve and said diaphragm 60 and adapted to close said valve on an increase in the pressure in said chamber and open said valve on a decrease in the pressure in said chamber, and means to prevent expansion of steam in said secondary, comprising a control 65 pipe connecting said diaphragm chamber, said secondary supply, said far end, and said return, said control pipe and return connection having a thermostatic trap valve therein.

14. In a heat transfer system having a conventional radiator system provided with a re-

turn pipe, a primary live steam supply pipe, a secondary exhaust steam supply pipe, means to admit exhaust steam to said system, means to admit live steam to said system, said live steam admitting means comprising a reducing and control valve for controlling said live steam admitting means, said valve having a diaphragm chamber, a diaphragm in said chamber, and means connecting said valve and said diaphragm and adapted to close said valve on an increase 10 in the pressure therein and open said valve on a decrease in the pressure therein, a vacuum pump connected to said return pipe, and a control pipe connecting said diaphragm chamber, said secondary exhaust steam supply pipe, and 15 said return pipe, and having a thermostatic trap valve in said control line connection to said return pipe.

15. In a heat transfer system having a plurality of radiators, a primary supply pipe therefor, a secondary supply pipe therefor having a far end and a return for said radiators, means to prevent expansion of steam in said secondary supply pipe, said means including a control valve between said supply pipes and a control pipe for 25 said valve connected to said secondary pipe and said far end and said return, said means including a valved aperture between said primary and secondary supply pipes, said aperture adapted to be varied inversely in proportion to the average 30 pressure in said secondary supply pipe.

16. In a heat transfer system having a plurality of radiators, a primary supply pipe therefor, a secondary supply pipe therefor having a far end and a return for said radiators, means to prevent expansion of steam in said secondary supply pipe and risers, said means including a control valve between said supply pipes and a control pipe for said valve connected to said secondary pipe and said far end and said return, said means including a valved aperture between said primary and secondary supply pipes, said aperture adapted to be varied inversely in proportion to the average pressure in said secondary supply pipe and risers. 45

17. In a heat transfer system having a plurality of radiators, a primary supply pipe therefor, a secondary supply pipe therefor having a far end and a return for said radiators, means to maintain uniform steam pressure in said secondary including said far end, said means including a control valve between said supply pipes and a control pipe for said valve connected to said secondary pipe and said far end and said return, said means including a valved aperture between said primary and secondary supply pipes, said aperture adapted to be varied inversely in proportion to the average pressure in said secondary supply pipe including said far end. 50

18. In a heat transfer system having a plurality of radiators, a primary supply pipe therefor, a secondary supply pipe therefor having a far end and a return for said radiators, means to maintain uniform steam pressure in said secondary including said far end and risers, said means including a control valve between said supply pipes and a control pipe for said valve connected to said secondary pipe and said far end and said return, said means including a valved aperture between said primary and secondary supply pipes, said aperture adapted to be varied inversely in proportion to the average pressure in said secondary supply pipe including said far end and risers. 65

19. In a heat transfer system having a plu- 70

- rality of radiators, a primary supply pipe therefor, a secondary supply pipe therefor having a far end and a return for said radiators, means to maintain uniform temperature and pressure in said secondary and risers, said means including a control valve between said supply pipes and a control pipe for said valve connected to said secondary pipe and said far end and said return, said means including a valved aperture between said primary and secondary supply pipes, said aperture adapted to be varied inversely in proportion to the average pressure in said secondary supply pipe and risers. 20
20. In a heat transfer system having a primary steam line and a secondary steam line having a far end, a regulating valve interposed between said primary and secondary lines, diaphragm actuated control means for said regulating valve, said control means adapted to close the regulating valve upon increase in pressure exerted against said diaphragm and open said valve upon a decrease in pressure exerted against said diaphragm, and means adapted to subject said control means to the average pressure in said secondary steam line including said far end. 25
21. In a heat transfer system having a primary steam line and a secondary steam line having a far end, a regulating valve interposed between said primary and secondary lines, diaphragm actuated control means for said regulating valve, said control means adapted to close the regulating valve upon increase in pressure exerted against said diaphragm and open said valve upon a decrease in pressure exerted against said diaphragm, and means adapted to subject said control means to the average pressure in said secondary steam line. 30
22. In a heat transfer system having a primary steam line and a secondary steam line having a far end, a regulating valve interposed between said primary and secondary lines, pressure actuated control means for said regulating valve, said control means adapted to close the regulating valve upon increase in pressure and open said valve upon a decrease in pressure, and means adapted to subject said control means to the average pressure in said secondary steam line including said far end. 35
23. In a heat transfer system having a primary steam line and a secondary steam line having a far end, a regulating valve interposed between said primary and secondary lines, pressure actuated control means for said regulating valve, said control means adapted to close the regulating valve upon increase in pressure and open said valve upon a decrease in pressure, and means adapted to subject said control means to the average pressure in said secondary steam line. 40
24. In a heat transfer system having a primary steam line and a secondary steam line having a far end, a regulating valve interposed between said primary and secondary lines, pressure actuated control means for said regulating valve, said control means adapted to close the regulating valve upon increase in pressure and open said valve upon a decrease in pressure, and means adapted to subject said control means to the instantaneous average pressure in said secondary steam line. 45
25. In a heat transfer system having a primary steam line and a secondary steam line, a regulating valve interposed between said primary and secondary lines, pressure actuated control means for said regulating valve, said control means adapted to maintain said regulating valve partially open, said open degree being determined by the average pressure in said secondary steam line. 50
26. In a heat transfer system having a primary steam line and a secondary steam line, a regulating valve interposed between said primary and secondary lines, pressure actuated control means for said regulating valve, said control means including balanced actuating means, the point of balance thereof being determined by the average pressure in said secondary steam line. 55
27. In a heating system having a primary steam line and a secondary steam line including a far end, and a return, means to control the admission of steam from said primary to said secondary, said means including an automatically actuatable valve, the actuating means for said valve including a member responsive to changes in the average pressure in said secondary, said far end and said return. 60
28. In a heat transfer system having a plurality of radiators, a primary supply pipe therefor, a secondary supply pipe therefor, having a near end and a far end, a pressure actuated control valve between said primary and secondary supply pipes, and an equalizing pressure control pipe connecting said valve actuator with the said near end and far end of said secondary supply pipe. 65
29. In a heat transfer system having a plurality of radiators, a primary supply pipe therefor, a secondary supply pipe therefor, having a near end and a far end, a return and vacuum means for said return, a pressure actuated control valve between said primary and secondary supply pipes, an equalizing pressure control pipe connecting said valve actuator with the said near end and far end of said secondary supply pipe, a by-pass connecting said control pipe and said return, and a thermostatic trap valve in said by-pass connection. 70

SAMUEL P. MILLER.
